UNITED STATES PATENT OFFICE.

ANDREW E. MATSON, OF EUREKA, CALIFORNIA.

TOBACCO-PIPE.

933,091.

Specification of Letters Patent. Patented Sept. 7, 1909.

Application filed January 19, 1909. Serial No. 473,055.

To all whom it may concern:

Be it known that I, ANDREW E. MATSON, a citizen of the United States, residing at Eureka, in the county of Humboldt and State of California, have invented certain new and useful Improvements in Tobacco-Pipes, of which the following is a specification, reference being had to the accompanying drawings.

10 This invention relates to improvements in pipes for smoking tobacco.

The object of the invention is to provide a simple and practical device of this character in which the smoke will be caused to travel through a circuitous passage in the stem and be thereby cooled and caused to deposit any nicotin which it may carry, a further object of the invention being to provide a device of this character in which the parts may be readily separated to permit them to be effectively cleaned.

With the above and other objects in view, the invention consists of the novel features of construction and the combination and arrangement of parts hereinafter fully described and claimed, and illustrated in the accompanying drawings, in which—

Figure 1 is a side elevation of the pipe; Fig. 2 is a longitudinal section; Figs. 3 and 4 are views of the opposite ends of the cylinder containing the circuitous smoke passage; Fig. 5 is a detail perspective of the sleeve upon the shank of the bowl; Fig. 6 is a detail view of one of the apertured disks or partitions; and Fig. 7 is a detail cross section taken on the plane indicated by the line 7—7 in Fig. 2.

The invention comprises a bowl 1 of any suitable form and construction to receive tobacco, a mouth piece 2 which may be straight, as shown, or suitably curved, and a stem 3 which unites the bowl and mouth piece. The stem 3 is in the form of a substantially cylindrical tube, one end of which is adapted to receive a reduced portion or shank 4 formed upon the bowl 1 and containing a smoke passage 5 which communicates with the bottom of the tobacco cavity in the bowl. Said shank 4 is cylindrical in form and is preferably made hollow or with a cavity 6 in which cotton or any filtering material may be placed if desired. Surrounding the shank 4 is a metal sleeve 7 of cylindrical form over which the tubular stem 3 fits. Said sleeve 7 is suitably fixed to the shank and in order to effect an air

tight connection between the sleeve and stem and to retain the latter upon the former, the sleeve 7 is formed in its outer face with an annular groove 8 adapted to receive a packing ring 9 of cork or other suitable material. The other end of the tubular stem 3 is adapted to receive an enlarged cylindrical head 10 upon the mouth piece 2, said head being formed with a groove 11 to receive a packing ring 12 similar to and for the same purpose as the ring 9. This construction, it will be noted, permits either or both the bowl and mouth piece to be removed from the stem for cleaning or other purposes and at the same time provides a friction fastening means and air tight joints between the parts.

Within the tubular stem 3 is a cylinder 13 and two centrally apertured disks or partitions 14, 15, the disk 14 being interposed between the other end 17 of the latter and the head 10 of the mouth piece, as shown in Fig. 2. The cylinder 13 has a circuitous smoke passage consisting of a plurality of longitudinally extending channels 18, which are in communication with each other through recesses or notches 19 at the opposite ends of the cylinder. The beginning of the passage is at a central cavity 20 in the end 16 of the cylinder opposite the central opening in the disk 14 while the end of said passage is at the center of the opposite end 17 of the cylinder, as will be seen upon reference to Fig. 2. By constructing the cylinder in this manner and having the disks 14, 15 centrally perforated they will close all the passages and recesses in the cylinder excepting the entrance and exit of the same no matter to what relative positions the bowl, stem and mouth piece may be turned. The cylinder 13 and the disks or partitions 14, 15 are removable from the stem so that these parts also may be quickly and thoroughly cleaned.

From the foregoing it will be seen that the use of the improved pipe will insure a cool smoke, and the absence of nicotin, since the latter will be deposited upon the walls of the circuitous passage in the cylinder 13. The peculiar construction of the several parts permits them to be readily taken apart and cleaned and causes them to be securely held together when assembled. The simple construction of the device also enables it to be produced at a small cost and renders it strong and durable.

Having thus described the invention what is-claimed is:

A tobacco pipe comprising a bowl having a shank provided with an annular groove, a 5 stem having a head formed with an annular groove, packing rings arranged in the groove of the shank and head, a tubular stem to receive said shank and head and engage said packing rings, a cylinder arranged in the 10 stem and having longitudinal passages and transverse connecting passages at its ends,

and perforated disks in said stem at the ends of said cylinder to close certain of the passages in the cylinder, substantially as described.

In testimony whereof I hereunto affix my signature in the presence of two witnesses.

ANDREW E. MATSON.
